UNITED STATES PATENT OFFICE.

ALBERTO RODRIGUEZ, OF SANTIAGO, CHILE.

APPARATUS FOR CLEANING AND COLLECTING SMOKE FROM FOUNDRY CHIMNEYS.

Application filed December 14, 1920. Serial No. 430,809.

To all whom it may concern:

Be it known that I, ALBERTO RODRIGUEZ, a citizen of the Republic of Chile, resident at Santiago, Chile, have invented new and useful Improvements in an Apparatus for Cleaning and Collecting Smoke from Foundry Chimneys, of which the following is a specification.

This invention relates to improvements in apparatus for storing the smoke and gases from the chimneys of smelters and other furnaces and recovering valuable or noxious particles therefrom.

The object of the invention is to provide an improved apparatus for storing such gas and smoke in order to recover valuable metallic or other particles therefrom, which would otherwise be carried off by the smoke and lost.

It is known that some furnaces of this type employ very powerful air ventilators or blowers to force the smoke and gases therefrom and that under such conditions small particles of minerals and fine powder are carried off by the smoke and lost.

My improved apparatus enables such loss to be avoided and also prevents the air in the neighborhood of such furnaces from being polluted and injuring the health of the inhabitants of the surrounding country.

In the accompanying drawings:

Figure 1 is a plan of an apparatus adapted for the operation of the process.

Figure 2 is partly a side elevation and partly a vertical sectional view of the same.

Fig. 3 is a detail of the air injecting type.

Figure 4 is a detail sectional view of one of the chambers or smoke receivers and its connections.

Around the chimney (1) of the establishment are constructed the smoke receivers (2) and (3) of any suitable number. On the top (4) of the chimney, the collector A is placed. This collector may be made of

iron or steel plates or other suitable material riveted together and lined inside with a coating of refractory and resisting material to protect it against the action of corrosive acids.

Said collector divides itself in two tubes (5) which lead in opposite directions and is provided in its interior with a baffle (6) which serves for the distribution of the smoke to both pipes.

A collector A is placed at a certain height above the chimney and with its bottom por-

tions being somewhat lower than the mouth of the chimney, so that the carrying away of the smoke in the operation of the process may not be disturbed by the wind which may blow from any side, and so that the smoke may rise straight up and come in contact with dividing point (6) and take the course indicated by pipes (5).

Experience has shown that the diameter of the collector must be 30% larger than the diameter of the chimney. The pipes (5) are nearly vertical and discharge at their lower ends into the receiving chambers (2) and (3) and the joint cross sectional area of said pipes must be greater than that of the chimney to avoid congestion of the smoke on its passage towards the receiving chambers.

On the top of the receiving chambers (2) and (3) and on both sides of pipes (5), centrifugal ventilators are placed. These ventilators blow compressed air into the smoke collector and into the pipes by means of tubes (8) and branch pipes (9) and (10) which lead into the collector and into the tubes (5) respectively. The upper ends of the pipes (10) are curved and arranged to discharge downwardly through the pipes (5) as at 11.

The object of this air injection is to constantly clean out the collector and tubes from ground mineral, soot and metallic particles which may adhere to the walls thereof; to produce an artificial draught to force the smoke quickly into the receiving chambers and finally to effect a rapid cooling off of the smoke.

Pipes (5) are provided with valves (12) by means of which the course of the smoke to the chambers may be temporarily cut-off, it being possible to alternate this operation in both tubes so that the removal of the material deposited in the chambers and conduits may be facilitated.

The smoke collector may be placed on top of the chimney in any convenient form whatever, it being preferable to place it on four or more iron plates riveted to the chimney. The stability of the collector and the pipes (5) may be in practice secured by the employment of suitable guys or other means, not here shown.

The smoke goes through tubes (5) to the receiving chambers (2) and (3) which may be made of wood, bricks, concrete or any other suitable material. These chambers

receive the smoke and store it and at the same time act as a distributing deposit. When these chambers are filled with smoke, it begins to pass therefrom through (13) 5 which may be of wood or any other suitable material and which serve to carry off the smoke to a long distance. Such pipes 13 may be placed on the level of the ground, suspended, or buried in the ground as may 10 be preferred. These pipes 13 have at a certain distance registers (14) to facilitate the cleaning of the residues deposited in them, and are connected with the upper side of chambers 2 and 3 as at 15. Traps (16) that 15 allow of the extracting of the residues deposited in them are arranged in said chambers 2, 3, and also in storage chambers 18 formed in structures to which said pipes 13 are connected, said chambers allowing of the 20 expansion of the smoke therein.

The smoke pipes (13) lead to a considerable distance from the furnaces and are provided at intervals of about five meters with registers (14) into which a broom may be 25 introduced for cleaning them.

To take advantage of the ground, the piping may be laid in zigzag form as shown in Fig. 1.

It is preferable that the inlet and outlet 30 of the smoke to the store-chambers 18 should be at points about midway between the tops and bottoms of said chambers, as shown at Fig. 4.

What I claim is:

35 1. In combination with a furnace chimney, a smoke collector at the top thereof, a receiving chamber, a pipe leading from said collector to said chamber, means to create draft upwardly through the chimney and

collector and downwardly through said 40 pipe, a storage chamber, a pipe leading to said storage chamber from said receiving chamber, a pipe leading from said storage chamber, and traps in said receiving and storage chambers. 45

2. In combination with a furnace chimney, a smoke collector at the top thereof and having return tubes and a baffle between said tubes, receiving chambers, pipes leading each from one of the return tubes to one of the receiving chambers, means to create draft upwardly through the chimney and collector and downwardly through said pipes, storage chambers, pipes connecting said storage chambers together and also to 50 said receiving chambers, and traps in said receiving chambers and storage chambers. 55

3. In combination with a furnace chimney, a smoke collector at the top thereof and having return tubes and a baffle between 60 said tubes, receiving chambers, pipes leading each from one of the return tubes to one of the receiving chambers, means to create draft upwardly through the chimney and collector and downwardly through said 65 pipes, storage chambers, pipes connecting said storage chambers together and also to said receiving chambers and storage chambers, said pipes and chambers having means to afford access to the interiors thereof to facilitate the removal of deposits therefrom. 70

In witness whereof I affix my signature,

ALBERTO RODRIGUEZ.
